DESIGN FOR A GAME BOARD

Joe L. Podgurski, Lansing, Ohio

Application September 9, 1940, Serial No. 94,898

Term of patent 14 years

To all whom it may concern:

Be it known that I, Joe L. Podgurski, a citizen of the United States, residing at Lansing, in the county of Belmont and State of Ohio, have invented a new, original, and ornamental Design for a Game Board, of which the following is a specification, reference being had to the accompanying drawing, forming a part thereof.

Fig. 1 is a plan view of a game board, showing my new design; and Fig. 2 is an edge view thereof.

I claim:

The ornamental design for a game board, as shown.

JOE L. PODGURSKI.
